MOTOR PUMP UNIT

Richard T. Cornelius, Minneapolis, Minn.

Application January 9, 1939, Serial No. 249,851

5 Claims. (Cl. 230—18)

My invention relates to motor pump units and has for an object to produce an extremely compact construction.

Another object of the invention resides in providing a motor pump unit in which the parts are arranged so as to produce a pleasing effect to the eye.

Another object of the invention resides in providing a motor pump unit in which the parts are symmetrically arranged.

A further object of the invention resides in providing a motor pump unit in which the base is utilized for the cooling of the pump diaphragm and exhaust valve.

Another object of the invention resides in constructing the pump unit with a separate housing and base and in clamping the pump diaphragm between the housing and base.

A feature of the invention resides in constructing the base with a central body portion overlying the diaphragm and in disposing within said body portion the exhaust valve of the pump.

Another object of the invention resides in constructing the base with cooling fins extending radially from and connected to said central body portion for cooling the same.

A still further object of the invention resides in constructing the housing to provide a compartment situated directly above the diaphragm.

An object of the invention resides in attaching a motor to said housing on one side of said compartment and in providing within the compartment mechanism operated by said motor for operating said diaphragm.

A feature of the invention resides in constructing the housing to provide a chamber on the other side of said compartment and directly opposite said motor.

An object of the invention resides in providing a port partly in said base and partly in said housing and extending through said diaphragm for bringing said exhaust valve into communication with the chamber.

Another object of the invention resides in operating the diaphragm with a connecting rod and in providing said connecting rod with an intake valve and in further utilizing said compartment as an intake chamber for delivering air to the intake valve of the pump.

A still further object of the invention resides in providing a regulating valve situated above said compartment and in further providing a port in the housing for bringing said regulating valve into communication with said chamber.

Other objects of the invention reside in the

novel combination and arrangement of parts and in the details of construction hereinafter illustrated and/or described.

In the drawings:

5 Fig. 1 is a longitudinal sectional view of a motor pump unit illustrating an embodiment of my invention and showing a portion of the same in elevation.

10 Fig. 2 is an elevational sectional view taken on line 2—2 of Fig. 1.

Fig. 3 is a plan sectional view taken on line 3—3 of Fig. 2.

15 Fig. 4 is a fragmentary elevational sectional view showing the diaphragm and exhaust valve of the unit and drawn to a larger scale.

20 My invention comprises a housing A which is supported on a base B. A pump mechanism C is carried by the housing and base and is operated by an electrical motor D. These various parts will now be described in detail.

25 The housing A consists of a horizontally positioned cylindrical wall 10 open at its ends. This wall has a tubular portion 11, at the lowermost part thereof, and a neck 12 at the upper portion of the same. Both of these parts are open at their ends and are connected to two partitions 13 and 14 which extend completely across the wall 10. Another partition 15 extends across the partitions 13 and 14 and divides the space between said partitions and the neck 12 into two compartments, indicated by the reference numeral 16 and 17.

30 The base B is constructed with a central body portion 18, which underlies the lowermost end of the tubular part 11 of housing A and which is secured thereto by means of screws 19. These screws extend through the part 18 and are threaded into a flange 21 extending inwardly from the part 11 which is accurately turned to form a seat. Clamped between the flange 11 and the central body portion 18 is a diaphragm 22 constructed of some flexible material adapted to be reciprocated and forming the movable element of the pump C. The diaphragm 22 forms a seal between the housing A and the base B and closes the lower end of compartment 17.

35 The base B is constructed, as best shown in Fig. 3, with a number of radially extending fins 23 which project outwardly from the central body portion 18. These fins are connected together and are reinforced by means of two circumferentially extending fins 24 and 25, the fin 24 being disposed at the edge of the central body portion and the fin 25 being situated medially of the 40 ends of the fins 23. A rim 26 is connected to

the outer ends of the fins 23. The various fins 23, 24, and 25 as well as the rim 26 serve to radiate heat outwardly from the central body portion 18 of the base B and to cool the diaphragm 22 and other parts associated therewith. The base B is supported on a number of rubber feet 27 which are attached to bosses 28 on the rim 26 by means of screws 29. These feet hold the base C elevated above the surface on which the motor pump unit rests.

The cylindrical wall 10 of housing A terminates at one end shortly past the tubular portion 11 of said housing and the neck 12. At this end motor D is attached to the housing. Motor D may be of any desired type and for this reason the construction has not been shown in detail. The motor shown is of the split-phase, single-phase alternating type and comprises a rotor 31, mounted on a shaft 32. The motor includes a case 33. One end of the shaft 32 is journaled in a bearing 35 received within a socket 36 formed in the partition 14 of housing A. The case 33 has an end bell 37 in which a bearing 34 is contained and in which the other end of the shaft 32 is journaled. The case 33 and end bell 37 are securely bolted to the cylindrical end wall 10 of housing A by means of bolts 38. The rotor 31 of motor D rotates within a field core 39 mounted in case 33 and which is energized by windings 41. A centrifugal switch 42 also forms part of the motor D.

The pump C includes the diaphragm 22, previously referred to. Overlying this diaphragm is a circular head 43. Upon the under surface of the diaphragm is disposed a cap 44 which is secured to the head 43 by means of screws 45. By means of this construction the head 43 is securely attached to the diaphragm 22. The head 43 has secured to it a connecting rod 46 which is constructed with two spaced T-shaped bars 47 connected together intermediate their ends by means of struts 48 and 49. The upper ends of these bars are connected to a split boss 50 which is bored to receive the outer race of a ball bearing 51. The said ball bearing is held in place by means of a screw 52 which draws the two parts of the boss together and clamps the same in position. The end of the shaft 32 is threaded, as designated at 53. To this threaded end of the shaft is screwed a counterweight 54. This counterweight is constructed with a pin 55, extending outwardly therefrom, which is eccentrically arranged with reference to the shaft 32. Pin 55 receives the inner race of the ball bearing 51 which is held in position on said pin by means of a cap screw 56, screwed into said pin. Upon rotation of the shaft 32 of motor D, the connecting rod 46 is caused to reciprocate and the pump diaphragm is moved in the desired manner.

In the central body portion 18 of base B is formed a concavity 57 which, in conjunction with the diaphragm 22, provides a pressure chamber 58. An intake valve 59, formed in the head 43, and cap 44 bring the compartment 17 into communication with the chamber 58. This valve is of the flapper type and consists of a flapper disc 61 adapted to seat against a seat 62 formed on the cap 44. A wire retainer 63, received in a groove 64, in cap 44, holds the disc 61 in position to be drawn up to the seat 62. The seat 62 encircles a valve opening 65 in the head 44 which communicates with a corresponding opening 66 in the head 43. It will thus be seen that, when the disc 61 is lowered, air may pass through the openings 66 and 65 and through the diaphragm

22 into chamber 58. An unloading spring 67, acting between the structure 49 and the disc 61, normally maintains said disc unseated from the seat 62 until the speed of the motor is sufficient to build up enough pressure in the chamber 58 to close said valve. The wall 10 of housing A, at the locality of the compartment 17, has an opening 68 formed in the same. This opening is closed by a grill 69 admitting air into the said compartment from the exterior. The grill 69 has supported thereon by means of a flange 70 a porous filter 170. This filter prevents dirt from entering the compartment 17.

The pump C includes an exhaust valve indicated in its entirety by the reference numeral 71. This valve is mounted in a boss 72, formed on the underside of the central body portion 18 of housing A. This boss is threaded at 73 to receive a plug 74 having a neck 75 extending upwardly therefrom. A screw cap 89 screwed into the threads 73 and engaging the lowermost portion of boss 72 covers the plug 74. Neck 75 engages the flange 76 of a tubular valve seat 77 which is received in a recess 78 in the part of the central body portion 18 opposite the boss 72. The valve seat 77 has an opening 79 through the center of the same which communicates with an opening 81 in the body portion 18. This latter opening is in communication with the chamber 58. A screen 82 overlies the opening 79 and valve seat 77 and prevents dirt from passing through the valve 71. The neck 75 has mounted in it a flapper valve disc 83 which is urged into engagement with the seat 77 by means of a compression coil spring 84. This coil spring is seated in a socket 85 in the plug 74 and normally holds the disc 83 into engagement with the seat 77. Air escapes from the opening 79 and through ports 86 in the neck 75 and into a chamber 87 formed at the upper portion of the boss 72. A port 88 is formed partly in the central body portion 18 of base B and partly in the neck 11 of housing A and extends through the diaphragm 22, as best shown in Fig. 4. This port communicates with the chamber 87.

The wall 10 of housing A projects outwardly beyond the neck 12 and tubular portion 11 at the end thereof opposite the motor D. To this end of the housing is attached, by means of screws 91, an end bell 92. End bell 92 forms in conjunction with the wall 10 and with the partition 13 which extends completely across the wall 10, a chamber indicated by the reference numeral 93. This chamber serves as a storage chamber for compressed air. Inasmuch as the port 88 extends through the wall 10, this port communicates with the chamber 93. An elbow 94 is screwed into the wall 10 and has attached to it a hose connection 95 by means of which compressed air may be conducted away from the chamber 93.

In the chamber 16 is mounted a pressure regulating valve 96. Since the construction of this valve does not form any feature of the instant invention, the same will not be described in detail. This valve includes a diaphragm 97 which is clamped between an annular seat 98, formed on the partition 15 and a ring 100. This diaphragm is urged downwardly through a compression coil spring 99. This spring is seated, at one end, against a collar 101 secured to diaphragm 97 and at its other end against a spring seat 102. A cap 104 is secured to the neck 12 by means of screws 105 and closes the upper portion of the compartment 16. A screw 103 is threaded in a boss 106, formed in cap 104, and engages the spring seat 102 and serves to control the pressure

exerted by the spring 99 on the diaphragm 97. The partition 15 is spaced from the diaphragm 97 to provide a chamber 107 therebetween. This chamber communicates through a port 108 in the partition 13 with the chamber 93 so that the diaphragm 97 is at all times subjected to the pressure in the chamber 93. The diaphragm 97 operates through suitable lever mechanism, not shown in detail, a mercury switch 109 (Fig. 2) which is connected in the circuit for the motor D and serves to operate said motor when the pressure in the chamber 93 falls below normal and to de-energize the motor when the pressure rises above normal.

For determining the pressure in the chamber 93, a pressure gauge 111 is utilized. This pressure gauge is received within a recess 112 in the cylindrical wall 10 of housing A. Said pressure gauge is provided with a pipe connection 113 which is screwed into the housing A and which 20 communicates through a port 114 with the chamber 107. Chamber 107 being in communication with chamber 93 through port 108, the gauge 111 indicates the pressure in the chamber 93.

The operation of my invention is as follows: When the pressure in chamber 93 drops, switch 109 is closed and the motor D energized. This causes the connecting rod 46 to be operated and the diaphragm 22 to be moved in the intended manner. Movement of the diaphragm draws air in through the grill 60 and into compartment 17 from which the air passes through the openings 66 in head 43 and 65 in cap 44 and through the valve 59 into chamber 58. As soon as the motor gains sufficient speed, flapper valve disc 61 closes and pressure builds up in chamber 58. The air compressed in this chamber passes through the passageways 71 and 79 and through the valve 71. Air on leaving this valve passes through the ports 36 into chamber 87 and from this chamber through port 88 and into chamber 93. From this chamber the air passes through the elbow 94 and hose connection 95 to the place where the same is to be used. Since the pressure regulating valve chamber 107 is in communication with chamber 93 through port 108, the pressure regulating valve 96 operates to open and close the switch 109 in accordance with the rise and fall of pressure within chamber 93. Pressure gauge 111, being in communication with chamber 93, indicates the pressure therein. Upon operation of the pump C heat is generated in the chamber 58. This heat is transferred largely to the central body portion 18 of base B and dissipated from the same through the various radiating fins 23, 24, 25 and 26. Due to the fact that these fins are integral with the said body portion the heat is rapidly conducted to the same. It will be noted that the base B is spaced from the housing A and also from the surface on which the motor pump unit rests. By means of this construction, the air is caused to rapidly circulate past the surfaces of the fins of base B and the heat is caused to be quickly dissipated. In this manner, the pump C is maintained cool and the diaphragm thereof and exhaust valve kept at a proper operating temperature.

My invention is highly advantageous in that the motor pump unit is extremely neat in appearance and compact, thereby requiring a minimum amount of space. The various parts of the pump unit are easily and sufficiently cooled by the base thereof whereby the pump operates at a suitable temperature. With my invention no ex-

ternal connections for conducting the air from one chamber to the other are needed since ports are formed in the various parts whereby such connections may be eliminated. All of the parts 5 of my invention are readily accessible and may be removed for inspection and repair whenever desired. By the arrangement of the parts, as shown, a substantial pressure chamber is provided whereby uniform pressure may be at all times procured.

Changes in the specific form of my invention, as herein disclosed, may be made within the scope of what is claimed without departing from the spirit of my invention.

Having described my invention, what I claim as new and desire to protect by Letters Patent is:

1. In a pump unit, a base, a housing carried by said base and secured thereto, a diaphragm clamped between said base and housing, said housing having a compartment directly over said diaphragm, and a chamber adjacent the same, mechanism within the compartment for operating said diaphragm, an exhaust valve in said base, a pressure regulating valve carried by said 25 housing, a port formed partly in said base and partly in said housing, and extending through said diaphragm, said port connecting said valve with said chamber and a second port in said housing connecting said chamber with said pressure regulating valve.

2. In a motor pump unit, a base, a housing carried by said base and secured thereto, a diaphragm clamped between said base and housing, said housing having a vertically extending compartment directly over said diaphragm, a motor attached to said housing on one side of said compartment, means within said compartment operated by said motor for moving said diaphragm, means forming a chamber directly opposite said motor and on the other side of said compartment, means forming a second compartment directly above said first compartment, a pressure regulating valve within said second compartment, an exhaust valve in said base and ports in said base and housing for bringing said chamber into communication with said regulating valve and said exhaust valve.

3. In a motor pump unit, a housing providing a central compartment, a motor carried by said housing on one side of said compartment, means forming a pressure chamber on the other side of said compartment, a base connected to said housing and disposed below said compartment, a pressure regulating valve carried by said housing and disposed above said compartment said valve controlling the operation of said motor, pump means at the lowermost portion of said compartment, means within said compartment and operated by said motor for operating the pump means, and ports in said housing for bringing said chamber in communication with said pressure regulating valve and said pump means.

4. In a pump unit, a base, a housing carried by said base and secured thereto, a diaphragm clamped between said base and housing, said housing having spaced walls within the same forming a compartment directly over said diaphragm, and a chamber adjacent one of said walls, a motor carried by the housing and having its shaft extending through the other wall, a crank operated by the motor shaft and disposed within said compartment, a connecting rod connected to said crank and reciprocating said diaphragm, said connecting rod being disposed within said compartment, an intake valve having a

passageway through said diaphragm communicating with said compartment, an inlet to said compartment, said base having a chamber opposite said compartment, and means for bringing said last named chamber into communication with said first named chamber.

5. In a pump unit, a base, a housing carried by said base and secured thereto, a diaphragm clamped between said base and housing, said housing having a compartment directly over said 10

diaphragm, and a chamber adjacent the same, mechanism within the compartment for operating said diaphragm, an exhaust valve in said base, a pressure regulating valve carried by said housing, a port connecting said valve with said chamber, and a second port in said housing connecting said chamber with said pressure regulating valve.

RICHARD T. CORNELIUS.
